(57) **CLAIM**

An ornamental design for a slot for multimedia furniture, as shown.

DESCRIPTION

FIG. 1 is a perspective view of a slot design for multimedia furniture;

FIG. 2 is a front view of the slot design for the multimedia furniture shown in FIG. 1;

FIG. 3 is a back view of the slot design for the multimedia furniture shown in FIG. 1;

FIG. 4 is a top or bottom view of the slot design for the multimedia furniture shown in FIG. 1; and,

FIG. 5 is a side view of the slot design for the multimedia furniture shown in FIG. 1.

The dashed lines immediately adjacent the shaded areas represent the bounds of the claimed design and form no part thereof.
